UNITED STATES PATENT OFFICE.

OSKAR MARTIN, OF BERGENFIELD, NEW JERSEY.

DESIGN FOR AN AXLE-BEARING FOR TOY WAGONS.

SPECIFICATION forming part of Design No. 28,431, dated March 29, 1898.

Application filed February 1, 1898. Serial No. 668,771. Term of patent 7 years.

To all whom it may concern:

Be it known that I, OSKAR MARTIN, a citizen of the United States, residing at Bergenfield, Bergen county, New Jersey, have invented and produced a new and original Design for Axle-Bearings for Toy Wagons, of which the following is a specification, reference being had to the accompanying drawings, forming part thereof.

Figure 1 is a perspective view of a front axle-bearing embodying my design; Fig. 2, a cross-section on line 2 2, Fig. 1.

The leading feature of my design consists of an axle-bearing for toy wagons of substantially uniform thickness and composed of an upper horizontal section, a pair of downwardly-extending curved arms, and perforated downwardly-extending projections at the ends of such arms.

The letter A represents the axle-bearing, made of rectangular shape in cross-section

and of substantially uniform thickness. The axle-bearing is composed of an upper horizontal section a and a pair of downwardly-extending ogee arms a' , that terminate in perforated projections a^2 . These projections have a straight outer face and a curved inner face, as shown. 25

The horizontal section a of the axle-bearing is shaped to form a flat central disk a^3 , 30 perforated, as at a^4 . From the curved arms a' of the axle-bearing extend forwardly a pair of perforated projections a^5 .

What I claim is—

The design for an axle-bearing for toy 35 wagons, substantially as herein shown and described.

OSKAR MARTIN.
